AMPOULE CUTTER

Edward F. Wenner, Columbus, Ohio, assignor to
H. R. Stallbohm, Lima, Ohio

Application April 20, 1950, Serial No. 157,017

10 Claims. (Cl. 49—48)

1

This invention relates to apparatus for removing a neck from a glass vessel, and more particularly to a cutter for opening an ampoule of the type which is hermetically sealed to hold a solution for hypodermic injection or the like. In general, the invention comprises a small, light weight container having means to receive and hold an ampoule with the neck thereof in a raised position, so that when the neck is removed the liquid level will be below the breaking point. A cutting element in the form of a scribe is provided for scoring the neck of the ampoule. There is also provided a hammer for snapping off the neck of the ampoule after the neck has been scored. A tape of absorbent material is used, in conjunction with a supply of disinfectant, to provide for cleaning the surface of the neck in the area where the break is to be made to prevent contamination of the ampoule contents.

One of the objects of this invention is to provide the cutter with a lower supporting member formed with a recessed surface to receive the shoulder of the ampoule and with a V type of knife edge surface to receive the neck of the ampoule. The shoulder and neck receiving surfaces are adapted to hold the ampoule with the neck projecting over the edge of the supporting member, and with the neck raised at an angle which provides for maintaining the liquid level below the point at which the neck is removed. Thus, when the neck is cut off the liquid does not spill from the ampoule.

Another object of the invention is to provide a slidably mounted member formed to engage the shoulder portion to hold the ampoule on the lower supporting member and with the neck held in a raised position. This member is maintained under spring tension so that it can adjust freely to compensate for any irregularities in the body formation of the ampoule. A finger operated lever is provided to control the movement of this member.

It is also an object to provide a cutting element in the form of a scribe for scoring the neck of the ampoule. This element has a spring mounting which provides for adjusting the element freely to compensate for any irregularities in the glass or neck of the ampoule. In the preferred construction this cutting element is carried by the slidably mounted shoulder engaging member. When the ampoule is mounted in position on the lower supporting member, the scribe line caused by rotating the ampoule neck in contact with the cutting element coincides i. e. lies in the same vertical plane with the knife edge

2

supporting the neck. This construction facilitates snapping the neck off clearly as described later.

An additional object is to provide a resilient holding means for gripping the neck of the ampoule when the ampoule is mounted in position on the lower supporting member. In the preferred form this holding means comprises a pair of rubber flaps positioned one on each side so as to extend along the sides of the neck when the ampoule is mounted for cutting. It has been found that this additional holding means on the neck tends to provide a cleaner break when the neck is struck by the hammer.

It is another object of the invention to provide a hammer for snapping off the neck of the ampoule after the neck has been scored. The hammer mechanism includes a spring means for applying the striking force to the hammer, a trip mechanism for releasing the hammer with a snap action, and a spring means for returning the hammer to the raised or striking position.

It is an additional object to provide means for supplying a disinfectant to clean the surface of the neck of the ampoule adjacent the area where the cut is made. In the preferred construction a tape of absorbent material extends across the top of the lower supporting member for this purpose. A pump is provided to supply the disinfectant to the tape as required.

Other objects and advantages of the invention will be apparent from the following description, the appended claims, and the accompanying drawings.

35 In the drawings, in which a preferred embodiment of the invention is illustrated,

Fig. 1 is a front elevational view of the case; Fig. 2 is a rear, vertical sectional view through the case showing the ampoule supports, cutting element, and hammer in the raised or striking position and in elevation and as seen from the rear in Fig. 1;

Fig. 3 is a side, vertical sectional view through the case as seen from the left side in Fig. 2;

40 Fig. 4 is a rear elevational view showing the hammer in the "down" position i. e. after striking the neck of the ampoule to remove the same;

Fig. 5 is a horizontal sectional view through the lower supporting member and taken on the line 5—5 of Fig. 4;

Fig. 6 is a view similar to Fig. 5 and taken on the line 6—6 of Fig. 4; and

Fig. 7 is a rear elevational view, partly in vertical section, of the upper engaging member.

55 Referring further to the drawings, the case 10

of Fig. 1 supports the frame 11. In the preferred construction, the case 10 is formed of plastic material and the frame 11 of metal. An opening is provided in the face or front of the case to receive the frame as shown in Fig. 1. Screws 16 extend through the front of the case and into shoulders on each side of the frame for securing the latter in position.

The lower ampoule supporting member 20, Fig. 6, is formed as an integral part of the frame. This supporting member is provided with a semi-circular, upwardly sloping and recessed surface area 21 formed to receive the shoulder portion 22 of the ampoule 23, Fig. 3. The surface 21 terminates along its upper edge in a knife edge formed with a V notch 25 therein. This notch provides for receiving and holding the neck portion 26 of the ampoule. As seen more clearly in Fig. 3, the notch 25 is above the shoulder portion 21 so that when the ampoule is mounted on member 20 the neck is raised at an angle of approximately 30 degrees from horizontal. Thus, when the neck is removed, the liquid level in the ampoule is maintained below the point at which the neck is cut away and spilling is avoided.

The ampoule is held on the supporting member 20 with the engaging member 30. This upper member is in the form of a slidably mounted gate having its lower edge provided with a semi-circular and recessed surface area 31 adapted to fit around the shoulder 22 of the ampoule as shown in Fig. 3. This surface 31 is tapered upwardly and smoothly curved to conform to the rounded shoulder portion of the ampoule, and extends from the front edge of member 30 to substantially the mid point of member 30 as viewed in Fig. 3. A similarly curved and formed surface 32 extends from the lower terminating edge of surface 31 upwardly to the back edge of member 30, as shown in Figs. 3 and 5. Surface 32 is formed to engage around the neck portion 26 of the ampoule. It will be understood by those skilled in this art that the radius of curvatures, slope, and shape of the surfaces 31 and 32 are such as to provide for engaging and holding different sizes of ampoules.

In the preferred construction the surface 21 is approximately $\frac{1}{8}$ of an inch across its greatest horizontal width, its greatest vertical height is about $\frac{1}{8}$ of an inch and its greatest slope length about $\frac{5}{8}$ of an inch. Surface 31 is formed to provide an opening with a rolled edge having a maximum inside width across the opening of about $\frac{7}{16}$ of an inch and a maximum outside width of about $\frac{11}{16}$ of an inch. Surface 32 has a maximum horizontal width of about $\frac{1}{2}$ of an inch and a vertical height of about $\frac{1}{4}$ of an inch. With these approximate dimensions ampoules varying in size from 1 to 20 cc. can be received.

Member 30 is slidably mounted between the guide members 37 and 38, Fig. 5, which are formed as an integral part of frame 11. The shoulder 39, Fig. 3, limits the upward travel of member 30 when it engages the edges 40 of the case 10. As shown in Fig. 7, an arm 42 extends downwardly from the side of member 30. This arm is adapted to engage one end of the pivotally mounted lever 43. The other end of lever 43 in turn engages the lower end of the slidably mounted lever 44. Lever 44 travels in the guide way 45, Fig. 5, formed in the frame 11. Bracket 46 holds lever 44 in place. A push button 48 is provided for finger operation of lever 44. When button 48 is depressed, lever 44 moves lever 43 to the dotted line position shown in Fig. 2. This

movement causes arm 42 to be raised together with member 30. A bore 49, Fig. 7, provided in the top of member 30 forms a seat for a coil spring 50 which abuts against the top of frame 11. Spring 50 maintains member 30 under tension at all times. With member 30 in a raised position an ampoule can be inserted as shown in Fig. 3. Then when the operator releases button 48 spring 50 forces member 30 down and into engagement with surface 31 fitting around the shoulder of the ampoule.

A cutting element 55 is provided for scoring the glass neck of the ampoule. In the preferred construction this cutting element is a diamond chip mounted in a holder 56, Fig. 7. The holder 56 is slidably mounted within a central passage 57 extending upwardly through member 30. The upper end of the holder is formed with a head which engages one end of the coil spring 59 carried in passage 57. A screw 60 closes the upper end of passage 57. Spring 59 maintains the holder under tension at all times. The holder is thus free to adjust, i. e. raise or lower, to compensate for any irregularity in the neck of the ampoule in the same manner as member 30 is free to adjust, i. e. raise or lower, to compensate for any irregularity in the shoulder portion of the ampoule. Holder 56 is aligned directly over the V notch 25 of member 20. Thus, when the ampoule is mounted, as shown in Fig. 3, the operator can rotate the ampoule with his fingers and the cutter 55 causes an annular score line to be formed around the neck. This score line coincides with the knife edge of notch 25, which facilitates removing the neck with a clean, sharp break as hereafter described.

Resilient holding means are provided to grip the neck portion of the ampoule which projects beyond the notch 25, as seen in Fig. 3. In the preferred form this holding means comprises a pair of rubber flaps 65 and 66. Flap 65 is held along one side by being crimped under the turned down edge 67 forming part of bracket 43. Flap 66 is similarly mounted, being crimped under the turned down edge 68 of bracket 69. These flaps form a gripping means extending along the projecting neck portion of the ampoule beyond the neck area which is scored. In operation it has been found that the cutter works satisfactorily without using the flaps 65 and 66; however, a cleaner break or cut of the neck is obtained when the flaps are used.

A hammer 75 is provided to snap off the neck of the ampoule after the neck has been scored. Hammer 75 is operated with a trip mechanism which provides the snap action of the hammer for breaking off the neck. Hammer 75 comprises an arm pivotally mounted to frame 11 with the screw 76. The hammer can swing from the raised position, shown in Fig. 2, to the lowered position, shown in Fig. 4. In swinging through this arc the hammer strikes the extended neck portion of the ampoule, which has been scored as previously described, and the blow of the hammer cracks the neck off cleanly. In order to obtain a clean, sharp break it is necessary for the hammer to swing with a snap action. To obtain this snap action the hammer is provided with a shoulder element 77. A detent 78 is pivotally mounted to the frame 11 with screw 79. The wire spring 80, one end of which is anchored to the pin 81 projecting from the frame, provides for holding the detent normally in the position shown in Fig. 2. In this position the lower end 82 of the

detent aligns with shoulder 71 and prevents the hammer from swinging downwardly.

The detent 78 is tripped, i. e. moved to the position shown in Fig. 4, so that the shoulder 71 can swing freely past the end 82 and allow the hammer to swing downwardly, by operating the lever 85. This lever slides in the guide way 38, Fig. 5, and is held therein by the bracket 69. A push button 87 facilitates depressing lever 85 until the pin 88, carried on the lever, strikes the inner end of the detent and moves it to the position shown in Fig. 4.

A coil spring 91 has one end thereof fastened to a pin on the lower end of lever 85 and the other end to the hammer 75. Thus when the lever 85 is depressed spring 91 is stretched and pulls downwardly on the hammer. However, the hammer cannot swing downwardly because of the engagement of shoulders 71 with the end 82 of the detent. In this way a considerable force is made available for the striking action. This force is released when the downward movement of lever 85 brings pin 88 into contact with the detent. A second coil spring 93, having one end fastened to the lower end of lever 85 and the other end to the top of bracket 69, provides for raising lever 85, and for moving spring 92 upwardly to return the hammer to the raised position. After the detent 78 has been tripped, spring 89 causes it to return to its normal position, i. e. as shown in Fig. 2.

Means are provided for supplying a disinfectant, for example alcohol, to wash the neck of the ampoule where the cut is to be made to prevent contamination of the ampoule contents. A container 97 is mounted in the case for the disinfectant. A finger operated pump mechanism, indicated generally at 98, is provided with a push button 99 which extends above the top of the case as seen in Fig. 3. A port 100, in the top of the case, is connected by the tube 101 to the top of container 97 and provides for replenishing the supply of disinfectant whenever necessary. A flexible tube 102 extends from the pump outlet and connects with the perforated spray pipe 103 fastened to the back of member 20, Fig. 2. A roll of cloth tape 105 is carried on the reel 106. The free end of the tape extends across the top of member 20 and notch 25 and down under the clip 107 on bar 108, Fig. 1, fastened to the front of the case. By pulling on the free end, the tape can be unrolled to provide a clean area over the notch 25 as desired. In operation the pump provides for spraying the disinfectant out of the pipe 103 and onto the tape covering notch 25. Then, since the neck of the ampoule is held in notch 25 and on the tape by member 30, rotation of the ampoule to score the neck also causes the neck to be wiped by the alcohol soaked tape.

To operate the cutter it is only necessary to push down on button 48 which causes member 30 to be moved, i. e. raised relative to the lower supporting member 20. The ampoule can then be inserted as shown in Fig. 3. When button 48 is released spring 50 causes member 30 to slide down until the surface 31 engages around the shoulder of the ampoule. The ampoule is then held with the shoulder supported between the surfaces 21 and 31, and with the neck supported in the V notch 25. The operator then slowly rotates the ampoule so that the cutter 55 scores the neck. This rotation of the ampoule also causes the neck to be wiped clean by the tape 105 which is in contact therewith. Following this operation button 87 is depressed to move lever 85. Movement of lever 85 causes spring 91 to be ex-

panded to apply tension to the hammer, and then releases the detent 79 which allows the hammer to strike with a snap action. The hammer blow snaps the neck off cleanly at the score line.

From the above description it will be apparent that the apparatus provided operates to accomplish the objects set forth. However, it is to be understood that the form shown and described is a preferred embodiment of the invention only. The invention is not limited to this precise form of apparatus, and changes can be made therein without departing from the scope of the invention which is defined in the appended claims.

I claim:

15. An ampoule cutter comprising a stationary supporting member for the ampoule; an engaging member adapted to hold the ampoule on said supporting member, with the neck of the ampoule held stationary and projecting over the edge of the supporting member, and with the neck raised at an angle which provides for maintaining the liquid level in the ampoule below the point at which the neck is cut off; a cutting element for scoring the neck of the ampoule; and a hammer including means for swinging the hammer with a snap action against the stationary neck for snapping off the neck of the ampoule after the neck has been scored.
20. An ampoule cutter comprising a supporting member for the ampoule; an engaging member formed to hold the ampoule on said supporting member; a resilient holding means positioned to engage the neck of the ampoule while the latter is held on the supporting member; a cutting element for scoring the neck of the ampoule; and a hammer for snapping off the neck of the ampoule after the neck has been scored.
25. An ampoule cutter comprising a supporting member for the ampoule having a recessed surface formed therein which engages one side of the ampoule at the shoulder portion thereof; a slide member having a recessed area adapted to engage said shoulder portion of the ampoule on the other side thereof and hold the ampoule on the supporting member with the neck portion of the ampoule raised at an angle; means for raising and lowering the slide member relative to the supporting member; a cutting element for scoring the neck portion of the ampoule; and a trip hammer mechanism for cracking off the neck of the ampoule after the neck has been scored.
30. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
35. An ampoule cutter for ampoules formed with a shoulder and neck portion comprising a frame including a lower supporting member for the ampoule having a shoulder receiving portion and a neck receiving portion; said shoulder and neck receiving portions supporting the ampoule with the neck thereof held in a raised position which
40. An ampoule cutter comprising a supporting member for the ampoule having a recessed surface formed therein which engages one side of the ampoule at the shoulder portion thereof; a slide member having a recessed area adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
45. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
50. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
55. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
60. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
65. An ampoule cutter comprising a supporting member for the ampoule having a V-notched knife edge for engaging the neck of the ampoule and formed with a recessed surface which engages one side of the ampoule at the shoulder portion thereof; a slide member formed with a recessed surface adapted to engage the other side of the shoulder of the ampoule and hold the ampoule on the supporting member with the neck on the knife edge and at an angle which prevents spilling the contents of the ampoule when the neck is removed; means for raising and lowering the slide member relative to the supporting member; a cutting element positioned to score the neck in the area engaging the knife edge; and a hammer for snapping off the neck of the ampoule after the neck has been scored.
70. An ampoule cutter for ampoules formed with a shoulder and neck portion comprising a frame including a lower supporting member for the ampoule having a shoulder receiving portion and a neck receiving portion; said shoulder and neck receiving portions supporting the ampoule with the neck thereof held in a raised position which

prevents the contents of the ampoule from spilling when the neck is removed; an upper member slidably mounted on the frame and including engaging means for holding the ampoule with the shoulder of the ampoule in the shoulder receiving portion and the neck in the neck receiving portion of the lower supporting member, said upper member having a spring mounted to provide for keeping the upper member under tension whereby the upper member can adjust to compensate for any irregularities in the shoulder or neck of the ampoule; a cutting element for scoring the neck of the ampoule carried by said upper member; and a hammer having a trip mechanism providing a snap action of the hammer for cracking off the neck of the ampoule after the neck has been scored.

6. An ampoule cutter for ampoules formed with a shoulder and neck portions comprising a supporting member for holding the ampoule in a stationary position and with the neck thereof raised above the shoulder; a slidably mounted member adapted to be moved into a position to engage and hold the ampoule on said supporting member; spring means for controlling the movement of said slidably mounted member; a lever for moving the slidably mounted member; a cutting element carried in said slidably mounted member for scoring the neck of the ampoule which includes means for adjusting the position of the cutting element relative to the neck of the ampoule; and a hammer for snapping off the neck of the ampoule after the neck has been scored including spring means for applying tension to the hammer and a trip mechanism for releasing the hammer with a snap action.

7. An ampoule cutter comprising a supporting member for the ampoule; a slidably mounted member adapted to engage and hold the ampoule on said supporting member; spring means for controlling the movement of said slidably mounted member; a lever for moving the slidably mounted member; a cutting element for scoring the neck of the ampoule including spring means for adjusting the position of the cutting element relative to the neck of the ampoule; a hammer for snapping off the neck of the ampoule after the neck has been scored; and means for operating the hammer including a spring for supply-

ing the striking force to the hammer, a trip mechanism for holding the hammer in a raised position while under spring tension, and a lever for releasing the trip mechanism whereby said

5 spring moves the hammer with a snap action.

8. An ampoule cutter comprising a supporting member for the ampoule; means for applying a disinfectant to the neck of the ampoule; an engaging member formed to hold the ampoule on 10 said supporting member; a cutting element for scoring the neck of the ampoule; and a hammer for snapping off the neck of the ampoule after the neck has been scored.

9. An ampoule cutter comprising a supporting member for the ampoule; a tape of material adapted to receive a disinfectant and extending across the top of said supporting member; an engaging member adapted to hold the ampoule on 20 said supporting member and with the neck of the ampoule in contact with the tape; a cutting element for scoring the neck of the ampoule; and a hammer for snapping off the neck of the ampoule after the neck has been scored.

10. An ampoule cutter comprising a supporting member for the ampoule; a tape of material adapted to receive a disinfectant and extending across the top of said supporting member; means for supplying disinfectant to said tape; an engaging member adapted to hold the ampoule on 25 said supporting member and with the neck of the ampoule in contact with the tape; a cutting element for scoring the neck of the ampoule; and a hammer for snapping off the neck of the ampoule after the neck has been scored.

EDWARD F. WENNER.
